DESIGN FOR A SLIPPER.

Design No. 18,507, dated August 7, 1888.

UNITED STATES PATENT OFFICE.

HUGO NOLLNER, OF JERSEY CITY, NEW JERSEY, ASSIGNOR TO SIEGMUND BAUM AND JACOB TARLOW, BOTH OF NEW YORK, N. Y.

DESIGN FOR A SLIPPER.

SPECIFICATION forming part of Design No. 18,507, dated August 7, 1888.

Application filed June 9, 1888. Serial No. 276,639. Term of patent 3½ years.

To all whom it may concern:

Be it known that I, HUGO NOLLNER, a citizen of the United States, and a resident of Jersey City, in the county of Hudson and State of New Jersey, have invented a certain new and useful and original Design Pattern and Configuration for Knit Slippers, of which the following is a specification, reference being had to the accompanying drawings, forming part thereof, the upper slipper of which I call hereinafter "Fig. 1" and the lower one "Fig. 2."

Figure 1 is a view of one side of my newly-designed knit slipper, showing the curve of the pattern around the front from one side to the other; and Fig. 2, a view of the other side of the slipper, both views being deemed necessary to fully illustrate my design.

The leading feature of my design consists of a herring-bone shaped pattern, (hereinafter explained,) with the body of the slipper on one side not corresponding with that on the other side, but having the pattern curved over and around the front half of the slipper, as more particularly shown in Fig. 1, and having a looped frame of knitted fabric standing out around the ankle, thus making a unique design framed with a looped and tasty frame at or near the top, setting off the whole.

The body of the slipper below the looped portion is made up by having alternate sections of raised portions *a a a* and depressed portions *bbb*. The raised portion is composed

of a double row of straight lines, *c c*, on each side of which a wavy double line, *d d*, is arranged. The depressed portions always remain at substantially right angles to the contiguous raised portions, all substantially as represented in both the figures.

On one side of the slipper the raised portions *a a* and depressed portions *b b* run substantially parallel with the sole of the slipper, and on the opposite side, in the front half of the slipper, these lines are perpendicular thereto.

A short way from the top of the slipper, at *g*, are the looped lines, of the same fabric as the body of the slipper, these loops forming a kind of frame around the ankle. Above these loops there are a few lines, *m*, running around in the direction of the length of the slipper, then lines *l* running upward at right angles thereto, then lines *n*, also in the direction of its length and forming the top of the slipper. Through the said lines *l* is a ribbon, *h*.

I claim—

The design for the shape and configuration of a knit slipper, substantially as herein shown and described.

Signed at New York city, in the county of New York and State of New York, this 24th day of May, A. D. 1888.

HUGO NOLLNER.

Witnesses:

H. S. SANDALL,
LEONARD B. SUTRO.
